UNITED STATES PATENT OFFICE.

CHARLES W. KAUFFMAN, OF DALE TOWNSHIP, McLEAN COUNTY,
ILLINOIS.

ROAD LEVELER AND SCRAPER.

No. 836,506.

Specification of Letters Patent.

Patented Nov. 20, 1906.

Application filed June 12, 1906. Serial No. 321,333.

To all whom it may concern:

Be it known that I, CHARLES W. KAUFFMAN, a citizen of the United States, and a resident of Dale township, in the county of McLean and State of Illinois, have invented a new and Improved Road Leveler and Scraper, of which the following is a full, clear, and exact description.

This invention is an improved machine for leveling and scraping roads, streets, or farm land and the like. The invention contemplates the production of a device of this character which shall be of simple construction and an effective means to level a road or other land, combined with a detachable drag-plate to adapt the machine to be used in the capacity of a scraper when desired.

Reference is to be had to the accompanying drawings, forming a part of this specification, in which similar characters of reference indicate corresponding parts in all the figures.

Figure 1 is a plan view of the machine complete. Fig. 2 is a side elevation of the same, and Fig. 3 is a fragmentary vertical sectional view taken through the pivotal connection between the leveler-beam and tongue substantially on the line 3 3 of Fig. 1.

The invention consists of a tongue 1 of suitable length pivotally connected to the center of a transverse leveler-beam 2 by means of a bolt 3, passing through the tongue and through a plate 4, secured to the top of the leveler-beam. At some suitable point forward of the leveler-beam a doubletree 5 is pivoted to the tongue on a bolt 6, said tree having connected to it at each end a swing-tree 7.

The leveler-beam 2 is rounded at each end, as shown at 8, in order that as it is being dragged along it will easily pass by roots or bushes with which it comes in contact. The bottom edge of this beam has a rearwardly inclined leveler-blade 9, said blade as it is pulled over the surface of the street or other ground cutting off the inequalities and bringing it to a uniform height. Each end of the beam has attached to it at its top edge a metal plate 10, projecting a slight distance over the beam at its front edge and overhanging the rear edge considerably farther, where it is attached to an angular brace-plate 11, the opposite end of the brace-plate being connected to the leveler-beam near the

blade 9 by bolts 12, these bolts being of sufficient length to pass through a detachable L-shaped drag-plate 13, having holes in its vertical portion to aline with the holes through the leveler-beam.

Plates 10^a are similar to the plates 10 and intermediate of them to provide additional bracing means for the leveler-beam, in that said plates have secured to them and to the beam 2 inclined plates 11^a, similar to the plates 11.

The rear end of the tongue has secured to it by bolts or other means a rearwardly-inclined spring-plate 14, supporting a seat 15 for the operator. Near this seat is a hand-wheel 16, fixed to the upper end of a rearwardly-inclined shaft 17, passing through the tongue and journaled in a metal bearing 18, said shaft having fixed to its lower end below the tongue a beveled pinion 19, designed to mesh with a pinion 20. The pinion 20 is journaled in the tongue 1 and carries at its upper end at the top of the tongue a grooved pulley 22 and underneath it a ratchet-wheel 22^a, designed to be engaged by a double-end pivoted pawl 22^b for locking the movement of the gearing in either direction. The pulley 22 has passed about it a rope, belt, or chain 23, passing forward about a pulley 24, fixed to a shaft 25, journaled in the tongue near the doubletree 5. Also fixed to the shaft 25 above and below the grooved pulley 24 are drums 26 and 27, respectively. These drums have attached to them, respectively, in some suitable manner ropes, chains, or other flexible connections 28 and 28^a, passing to and connected with springs 29, engaged in the front ends of the plates 10. These springs are for the purpose of taking up the slack in the ropes or allowing them to elongate when the leveler-beam is turned in an angular position.

The forward ends of the plates 10^a are connected with a curved or semicircular plate 30, concentric with the bolt 3 and offset downwardly near its ends at 31 in order that a space will be provided between this and the tongue which passes over it, said tongue carrying a roller 32, journaled underneath it, bearing on the plate 30, which partially sustains its weight.

In the operation of the machine the leveler-beam is used solely with the leveler-blade or in connection with the drag-plate 13, accord-

ing to the nature of the work which is to be performed. The operator seats himself on the seat 15 and drives the horses hitched to the swingletrees 7 and also operates the hand-wheel 16 to throw the leveler-beam at an angle to the tongue in order to discharge the dirt collected by this beam at either side of the road or at the road's center. The beam is locked in any desired angular position by the operator working with his foot the pawl 22^b to engage the teeth of the ratchet-wheel 22^a. As the hand-wheel is turned the rope 28 or 28^a is wound or unwound about its respective drum, according to the direction in which the hand-wheel is turned, positively forcing the beam and tongue to take an angular relation.

Although I have described the invention in detail, it is to be understood that its scope is limited by the annexed claims only.

Having thus described my invention, I claim as new and desire to secure by Letters Patent—

1. In a device of the character described, the combination of a tongue, hitching means connected thereto, a beam pivotally connected to the tongue, leveling means carried by the beam, means for reinforcing the beam, drums journaled on the tongue, flexible connections attached to the drums, springs for connecting the flexible connections to the beam, and means for winding up one of said flexible connections and unwinding the other to turn the beam at an angle to the tongue, as described.

2. In a device of the character described, the combination of a tongue, a leveler-blade at the lower end of the leveler-beam, a seat attached to the tongue, and an operating-lever journaled in the tongue adjacent to the seat, for drawing the beam and tongue at an angle to each other.

3. In a device of the character described, a tongue and a beam pivotally connected together, means for leveling the ground, carried

by the beam, a flexible connection between the tongue and beam, and means for operating said connection to throw the tongue and beam at an angle to each other, for the purpose described.

4. In a device of the character described, the combination of a tongue, a beam to which it is pivotally connected, scraping and leveling means carried by the beam, means for reinforcing the beam, a curved bar fixed to the beam and passing under the tongue, a roller journaled at the under face of the tongue over the curved bar and adapted to bear upon it, a seat for the operator, attached to the tongue, and operating means adjacent to the seat to throw the tongue and beam at an angle to each other, for the purpose described.

5. In a device of the character described, the combination of a tongue, a beam pivotally connected with the tongue, leveling means carried by the beam, a seat for the operator, attached to the tongue, an inclined shaft journaled in the tongue having a hand-wheel at its upper end adjacent to the seat, drums fixed to a shaft journaled in the tongue, flexible connections attached to the drums and connected with the ends of the beam, and gearing intermediate the shaft and hand-wheel for turning the drums in either direction to throw the beam and tongue in an angular relation, as described.

6. In a device of the character described, a tongue, a leveling-beam to which the tongue is pivotally connected, flexible connections provided with resilient means between the tongue and beam, and means for alternately winding and unwinding the flexible connections, as described.

In testimony whereof I have signed my name to this specification in the presence of two subscribing witnesses.

CHARLES W. KAUFFMAN.
